UNITED STATES PATENT OFFICE.

STEPHEN P. RUGGLES, OF BOSTON, MASSACHUSETTS.

PRINTING-PRESS.

Specification of Letters Patent No. 10,588, dated February 28, 1854.

To all whom it may concern:

Be it known that I, STEPHEN P. RUGGLES, of Boston, in the county of Suffolk and State of Massachusetts, have invented certain new and useful Improvements in Printing-Presses, which I denominate a "Combination-Press;" and I do hereby declare the following to be a full, clear, and exact description of the same, reference being had to the accompanying drawings, making a part hereof, in which—

Figure 1, represents a top view or plan of the press. Fig. 2, represents a view from one of the sides. Fig. 3, represents a view of the side opposite to Fig. 2, and Fig. 4, represents a vertical longitudinal section through the press; Fig. 5, a view of a detached portion.

Similar letters in the several figures denote like parts.

The nature of my invention consists, more particularly, in the general arrangement of the various parts of a printing press; so as to combine great utility, with the simplest and cheapest manner of construction.

To enable others skilled in the art to make and use my invention, I will proceed to describe the same with reference to the drawings.

The frame A may be suitably and substantially built of cast iron, and in proper bearings therein is placed the shaft B, carrying the balance wheel C, through which motion may be given to the several parts of the press by hand or any other power. At or about the center of the press on the shaft B, is secured a spur wheel D, which meshes into and rotates a large gear wheel E, on a shaft F, also supported in the frame A. On said shaft F, is also placed the eccentric pins (one only being seen in the section Fig. 4) for forcing up the platen, or for throwing off the impression, and which will be, hereafter, more fully described. The shaft F, carries on its extreme ends, outside of the frame of the press, the two cam wheels G, (Fig. 2), and H, (Fig. 3), in the face of which cam wheels are cut the cam grooves (respectively) a, b, into which pins c, d on the arms I, J, work and give to the rock shaft K, the motions necessary to operate

the inking rollers, and the platen, at proper intervals, so that the motions of one shall not interfere with those of the other, it being necessary to vary their respective motions, at such periods of their movement, as they may be performing their office in; or when moving out of the way for the operation of some other device over the same space. The shaft K is divided in its center—one part having a step or support in the other, so that each part may turn independent of the other, as they are operated by their respective cams G, H, or the cam grooves therein. The cam groove a, on the cam wheel G, through the pin c, arm I, and its part of the rock shaft K, operates, by means of the bent lever L, the inking rollers e, e, causing them at regular intervals to pass over and ink the form—the shape of the cam being such that said rollers shall travel to and from their work with great rapidity, while during the inking of the form they shall travel more slowly, and do more perfect work. The cam grooves b, on the cam wheel H, by means of the pin d, arm J, and the other part of the rock shaft K, operates, by means of the bent lever or arm M, the platen-plate N with the sheet holder, thereon, the cam movements being so regulated relatively with the motion of the inking rollers, as to give each time to perform its special office without coming in contact with each other.

The inking rollers e, e, (Fig. 4,) are hung in arms i, (one only being seen in the section) which are bent up at right angles to, and are a part of, a rod or shaft g, around which rod, is coiled a spring or springs j, (Fig. 1,) which admits of the inking rollers being forced up to, and moving over, the form in a perfect plane instead of moving in the arc of a circle, as they would do, if rigidly fixed to the bent lever L. These coiled springs, also, when the rollers are carried down below the form after inking it, throw the rollers e, e, out against the supply roller O, to be recharged with ink. It is obvious that the form being a perfect flat surface, could not be properly inked by rollers moving in the arc of a circle, but by hanging the rollers to the spring rod, they move by means of a guide h, in a perfect

plane across the form, and after inking and dropping below the form are thrown by the uncoiling of the springs *j*, against the supply roller *O*,—the arm or bent lever *L* carrying them from one to the other.

- 5 The sheet is held to the platen plate *N*, by means of the springs *k*, which (as they are hung to the platen plate) move with it, and are forced up against the sheet by the rod *l*.
 10 The spring holders *k*, are hung on a rod *f*, and in said rod longitudinally is cut a slot (represented by a red line in Fig. 1,) into which a small projection on the boss or sleeve of the spring fits, and admits of said springs being run out or in on said rod *f*, so as to be adjusted to the size or shape of the paper to be printed upon. Around the rod *f*, is coiled a small spring *m*, which winds up as the platen plate *N*, goes down—
 15 20 the spring holders *k*, being forced up against the paper by the fixed rod or bar *n*, against which they rest. When the platen comes up, the uncoiling of the spring *m*, throws out the spring holders *k*, as seen in the drawing, 25 and releases the sheet.

The ink trough *P*, is hung upon the frame by springs *o*, *o*, which allows it, and ink roller *Q*, hung in it, to adjust and adapt themselves to the intermediate ink roller *R*.
 30 which is placed between the ink rollers *O*, *Q*, for conveying the ink from one to the other of said rollers. On the end of the roller *Q*, is a ratch *p*, into which a weighted pawl may work so as to rotate the roller in the ink trough, and said roller may also be grooved with shallow small grooves, for better carrying up and distributing the ink.
 35 The roller *O*, may have a double thread or screw cut upon one of its ends for giving it 40 a transverse motion, in addition to its rotary motion, which last it receives from the pulley *S*, on the shaft *B* by means of a twisted or crossed belt *q*, passing around it, and around the pulley *T*, which is attached 45 to the axis of said roller *O*.

The paper table *U*, is so placed, that the sheets, or other thing to be printed upon may be conveniently placed on the platen plate *N*, where it is caught by the spring holders, as before described and carried down to where it is to receive the impression—the form having been previously inked by the rollers *e*, *e*. The eccentric pin *r* on the shaft *F*, then catches into the toggle arm *V*, and forces up the platen against the form. The bed *W* is permanently fixed to the frame by the screws *s*, *s*, and should be sufficiently rigid to receive the pressure of the platen. The guide piece *h*, has arms *t*, *t*, at each end of it which unite in a spring plate (shown by dotted lines in Fig. 4) said plate having slots in it through which set

screws pass, by which the inking rollers may be allowed to yield or adjust themselves to the platen plate.

65

The platen *X*, is hung upon the curved arms *Y*, (one only being seen in Fig. 4)—the other ends of said arms *Y*, being attached to a rock shaft *Z*, which is supported in the frame of the press. In the same rock 70 shaft *Z*, is also placed, the spring arms *u* (one only being seen) which support the inking roller *R*, and which roller, when the platen is forced up against the bed or form, is thrown, by the partial rotation of said 75 shaft *Z*, against the roller *Q* in the ink trough for the purpose of receiving another supply of ink.

The impression is regulated by means of four screws *v*, *v*, (two only being seen in Fig. 4, in red lines) one at each corner of the platen, by which means a form may be worked in any part of the platen. The bed being stationary, and the platen vibrating, but confined at the two corners, cannot yield 85 out of its plane, these set screws therefore make up a perfect adjustment of the impression.

80

The toggle arm *V*, has a cord *w*, attached to it which passes up and around a pulley *x*, to which there is a handle *y*, conveniently placed near where the paper is placed on the platen plate, so that the operator, by pushing down said handle, may throw off the impression.

90

Fig. 5, represents a perspective view of the spring arm or plate which carries the guard or guide plate *h*, detached from the press, and shown in place in dotted lines in Fig. 4, in which 1 represents the slots, and 2 the set screws therein to allow it to move from the platen or platen plate, and 3 a coiled spring behind it, (represented in dotted lines), one end of which spring is fastened to said plate—the other end to the frame of the press, the object of the spring being to allow the rollers to adjust themselves to the form and at the same time control them in the extent of their movement. When the rollers have passed down, and the impression is taking the guides *h* (there being one at each side of the press,) as well as the spring holders *k* pass into recesses in the form or the spaces between the forms, so as to allow the sheet to come fairly up to 100 the form.

95

Having thus fully described the nature of my invention what I claim therein as new and desire to secure by Letters Patent is—

110

1. In combination with the curved arm *L*, for carrying the inking rollers to and from the form, the spring plates with the guides *h*, at each end of the rollers, for causing said rollers to pass over the form in a plane

120

parallel to the form, their general motion being in the arc of a circle, substantially as described.

2. I also claim hanging the platen X, and 5 the intermediate ink roller R, to the same rock shaft Z, by their respective arms Y, and u, so that the vibration of the platen, shall throw the intermediate roller, first, to the grooved ink roller Q, and then to the

ink bearer O, for the purpose of receiving 10 and distributing the ink from the ink trough at every vibration of the platen substantially as described.

STEPHEN P. RUGGLES.
